(57) **CLAIM**

The ornamental design for a clip for cushion, as shown and described.

DESCRIPTION

FIG. 1 is a perspective view of a clip for cushion;
FIG. 2 is a left side view of the clip for cushion of FIG. 1;
FIG. 3 is a right side view of the clip for cushion of FIG. 1;
FIG. 4 is a front view of the clip for cushion of FIG. 1;
FIG. 5 is a rear view of the clip for cushion of FIG. 1;
FIG. 6 is a top view of the clip for cushion of FIG. 1; and,
FIG. 7 is a bottom view of the clip for cushion of FIG. 1.
The claimed clip for cushion is used to attach features to a cushion, and could be part of a seat.

1 Claim, 5 Drawing Sheets
